UNITED STATES PATENT OFFICE

ARNOLD W. NEWMAN, OF ALVIN, TEXAS

JACK

Application filed May 17, 1928. Serial No. 278,371.

This invention relates to new and useful improvements in a jack.

One object of the invention is to provide a tool of the character described specially 5 designed for use in connecting a motor vehicle spring to the shackle by means of which the spring end is connected to its perch.

In repairing the springs of certain types 10 of motor vehicles it is sometimes necessary to disconnect the spring end from the shackle by means of which it is connected to the spring perch and when the repairs have been made it is quite difficult with the 15 tools now in use, to reconnect the spring end to its perch. The jack herein described is intended for use in making such connection.

Another object of the invention is to provide 20 a jack of the character described which is of simple construction, may be cheaply produced and is very efficient in use.

With the above and other objects in view this invention has particular relation to certain 25 novel features of construction operation and arrangement of parts an example of which is given in this specification and illustrated in the accompanying drawings, wherein:—

30 Figure 1 shows a plan view of the jack. Figure 2 shows a longitudinal vertical sectional view thereof as applied in use, and

35 Figure 3 shows a cross sectional view thereof.

Referring now more particularly to the drawings, wherein like numerals of reference designate similar parts in each of the figures the numeral 1 designates the frame 40 of the jack as a whole. This frame has the downwardly turned end flanges 2, 2 forming supporting legs whose lower ends have arcuate seats 3, 3 designed to rest on the vehicle axle, 4. The frame also has the 45 depending side flanges 5, 5. The frame has a long longitudinal slot 6 therein and slidably mounted on the frame there is a head 7 which is confined to longitudinal movement on the frame by means of a set screw 8 50 which is fitted upwardly through said slot

and is screwed into said head and the head of this set screw engages the under side of the frame and prevents the detachment of the head 7 from the frame.

Upstanding from one end of the frame 55 there is a holder 9 having the top and side flanges 10 and 11, 11 respectively. Seated in this holder, between said flanges, there is a nut 12 which is held against turning by said holder. A jack screw 13 is threaded through said nut and works loosely through an opening 14 in the holder. The outer end of this jack screw has a polygonal head 15 to receive a wrench by means of which it may be turned and its other end 60 has a swivelling connection with the head 7.

The jack may be mounted on the axle 4, at the desired place, with its legs 2 resting on said axle. The jack may be secured in place by means of the side links 16, 16 70 whose upper ends are connected to the side flanges 5, 5 and whose lower ends are fitted through end bearings in the cross yoke 17 and are threaded to receive the clamp nuts 18, 18 which retain the yoke on said links. The links are arranged one on each side of the axle 4, with the yoke clamped against the under side of said axle.

The jack, as so located, is so disposed that the head 7 may be engaged against the inner side of the end bearing 19 of the leaf spring 20, of the vehicle. The jack screw 13 may now be turned so as to force the end of the spring outwardly into such position, relative to the corresponding spring perch 21, that the connecting shackle may be readily connected to said spring end and perch.

While the jack has been shown as applied to the work of connecting a spring of an automobile to its shackle it is also capable of other similar uses.

It is obvious that mechanical changes may be made and equivalents substituted for the parts shown and I reserve the right to make such changes and substitutions within the scope of the appended claims.

What I claim is:—

1. A jack including a frame adapted to be mounted on a vehicle axle, a head mov- 100

able on the frame, a holder carried by and upstanding from the frame, said holder having overturned top and side flanges, a nut in said holder held against turning by said flanges, a jack screw threaded through said nut and having a swivelling connection with said head.

5 2. A jack including a frame adapted to be mounted on a vehicle axle, a head movable on the frame, a holder carried by and integral with the frame, a nut in said holder, a jack screw threaded through said nut and having a swivelling connection with said head, legs depending from the frame and formed with arcuate seats to receive said 10 axle, and means for securing said frame to said axle.

15 3. A jack including a frame having end legs for supporting the frame on a vehicle axle, and formed with arcuate seats to receive said axle, a head movable on the frame, a holder on the frame, a nut in said holder, a jack screw threaded through the nut and connected to said head, and means for 20 clamping said frame onto said axle.

25 4. A jack including a frame formed to fit on a vehicle axle, a head movable on said frame, a jack screw operable against said head, a holder upstanding from the frame and having overturned flanges, a nut between said flanges with which said screw has a threaded connection, means for clamping the frame onto said axle, said clamping means including a yoke and side links connected at one end to said frame and at their 30 other ends to the respective ends of said yoke.

35 In testimony whereof I have signed my name to this specification.

40 ARNOLD W. NEWMAN.
